DOOR CLOSER AND CHECK

William L. Sheppard, Detroit, Mich., assignor, by direct and mesne assignments, to Herbert Morley, Grosse Pointe, Mich., and Theodore R. Bush, Royal Oak, Mich., jointly

Application June 18, 1938, Serial No. 214,515

7 Claims. (Cl. 16—53)

This invention relates to a new and improved form of door closer and check.

A principal object of the invention is to provide a door closer and check which is simpler in design and hence can be constructed more cheaply than door closers now being manufactured.

Another object of the invention is to provide a door closer with a new and improved form of checking device for slowing down the closing movement of the door just before the end of its travel.

Other objects and advantages of the invention will be apparent from a consideration of the following specification, taken in conjunction with the accompanying drawing, of which there is one sheet and wherein:

Fig. 1 is a plan view of the device embodying the invention, shown applied to a door;

Fig. 2 is a vertical sectional view taken in a plane along the line 2—2 of Fig. 1;

Fig. 3 is a horizontal section taken along the line 3—3 of Fig. 2; and

Fig. 4 is a developed view of the cam.

Referring to Fig. 1, there is shown a door closer 10, shown applied to a door for closing the same, the door being indicated at 12, and the wall or casing upon which the door 12 is hung being indicated at 14. The closer 10 may be secured to the wall 14, such as by means of a pair of screws 16. The door closer includes a linkage device comprising a pair of arms 18 and 20, pivotally connected together at 22, the arm 20 being pivotally connected to the door 12 by a bracket 24, and the arm 18 being connected to a shaft 26 of the closing device.

The door closer and check consists, as illustrated in Fig. 2, of a body member 28, providing a cylinder and closed by a cap or end plate 30 secured thereto, such as by means of screws 32. The end plate 30 may be provided with a flanged portion 34, provided with apertures 36, by means of which the screws 16 may secure the door closer to the wall 14. The screws 32 may pass through suitable openings in the cover 30 and be threaded into tapped holes provided in the wall of the body member 28.

The body member 28 provides a cylinder in which there is arranged a spring 38, the end 40 thereof being anchored, as illustrated, to the body member 28, and the other end 42 of the spring being turned inwardly so as to hook around an arm 44 carried by a cam 46. The cam 46 includes a cylindrical portion of substantially the same diameter as the cylinder of the

body member 28, a cam surface 48, and the shaft 26, which projects through an aperture in the cover 30. The arm 18 is connected by means of a bolt 50 to a clamp 52 and also by means of a bolt 54, directly to the shaft 26, so that upon movement of the arm about the center of the shaft as a pivot, the shaft 26 and cam 46 will rotate. The clamp 52 may be secured to the shaft 26 by means of a pair of bolts 58. A gland 60 may be formed between the cam 46 and the cover 30 so as to prevent the escape of fluid from the cylinder 62.

The body member 28 may be formed to provide a second cylinder 64 of smaller diameter than the cylinder 62 and in which a piston 66 is reciprocable. The piston 66 is formed to include a valve, so as to pass fluid into the cylinder 64 upon upward movement of the piston. The valve and valve passageway comprise a passageway 68, provided in the connecting rod 70 of the piston, a valve seat 72, a valve member 74, which closes the valve seat, a valve spring 76, which biases the valve member 74 to its seat, an apertured retainer 78, which forms a seat for the valve spring 76, and a leather cup 80, which provides a face for the piston 66.

A spring 82 biases the piston 66 upwardly. The cylinder 64 is provided with an outlet 86, the size of which is controlled by a metering pin 88, provided on the end of a threaded plug 90, adjustable in a tapped hole provided in the body member 28 and closed by the bolt 94. The end of the piston rod 70 engages a lever 96 pivoted at 98 by a pin to a lug 100 carried by a removable portion 102 of the body member 28, the portion 102 being removably secured to the body member by bolts 104. The lever 96 may include a roller or sleeve 106 which rolls upon or engages the cam face 48 of the cam 46.

Upon opening movement of the door, the lug 44 winds up the spring 38, the cam 46 being rotated in a clockwise direction, looking at Fig. 1, by the opening movement of the door. Fig. 2 shows the relationship of the parts when the door is partially open. Upon opening movement of the door, the cam face 48 permits the lever 96 and the piston 66 to rise, whereupon liquid by-passes the piston 66 into the cylinder 64. The spring 38 operates to return the door to a closed position and acts through the intermediary of lug 44, cam 46, and linkage 18, 20 and 24. The cam surface 48 preferably is located so that, for example, when the door is within twenty degrees of closing, the cam will engage the roller 106 and, through lever 96, force the

piston 66 downwardly in the cylinder 64 so as to displace oil therefrom. The outlet 86 from the cylinder 64 is of such size as to restrict the flow of oil from the cylinder 64 and thereby check the closing movement of the door. The piston is forced downwardly by the cam face 48 until the door is within one or two degrees of closing, when the flat 49 on the cam permits the spring 38 to close the door without any further check.

10 Due to the adjustable connection between the arm 18 and the shaft 26, the relation of the cam face 48 to the closing position of the door may be varied so as to check the door at any desired position. Further, by changing the design of the 15 cam face 48, the checking action of the door may be modified. The regulation of the size of the outlet 86 from the cylinder 64 would also vary the checking action. The liquid used in the cylinders 64 and 62 preferably stands at a 20 level close to the top thereof, so as to insure the filling of the cylinder 64, and this oil may be of such viscosity and character as to be substantially unaffected by changes in temperature due to changes in seasons.

25 The piston 66 and cylinder 64 form a dashpot, which functions to check closing movement of the door.

While the invention has been described with some detail, it is to be understood that the description is for the purpose of illustration only and is not definitive of the limits of the inventive idea. The right is reserved to make such changes in the details of construction and arrangement of parts as will fall within the purview of the 35 attached claims.

I claim:

1. In a device of the class described, a rotatable member, a spring operable for turning said member in one direction, and means including a dashpot for checking movement of said member in one direction during only a portion of the permissible movement thereof.

2. Door closer construction comprising a pair of relatively movable members, one of said members being adapted to be connected to a door and the other of said members being adapted to be connected to a wall upon which said door is hung, a spring arranged between said members and adapted to move one relative to the other to effect closing movement of said door, and means for checking only a portion of said relative movement comprising a dashpot.

3. Door closer construction comprising a pair of relatively movable members, one of said members being adapted to be connected to a closure

and the other of said members being adapted to be connected to a wall upon which said closure is hung, a spring operatively associated with said members and adapted to move one of said members relative to the other to effect closing movement of said closure, and means for checking only a portion of said relative movement comprising a dashpot carried by one of said members and a linkage including cam means between said dashpot and the other of said members.

4. Door closer construction comprising a pair of cylinders, a rotatable cam in one of said cylinders, a piston in the other of said cylinders, a spring for turning said cam in one direction, a lever pivoted to one of said cylinders and operatively arranged between said cam and said piston so as to move said piston in one direction upon rotation of said cam, spring means opposing movement of said piston, said cylinder in which said piston is arranged being adapted to contain fluid, and means for restricting the escape of fluid from said cylinder.

5. Door closer construction comprising a cylinder, a closure therefor, a cam rotatably mounted in said cylinder and having a portion projecting through an opening in said closure, a spring arranged within said cylinder and operable for rotating said cam, a dashpot arranged within said cylinder and including a piston, a lever pivoted at one end thereof to said cylinder and having its free end operatively associated with said piston, said lever being engageable by said cam on rotation thereof for moving said piston.

6. Door closer construction comprising a body member formed to provide a cylinder, a piston in said cylinder, a restricted outlet from said cylinder, said cylinder being adapted to be supplied with liquid, a rotatable cam and an operative connection between said cam and said piston so as to move said piston in said cylinder upon rotation of said cam, and means for rotating said cam, said cam being provided with a flat which permits rotation thereof without corresponding movement of said piston.

7. Door closer construction comprising a sleeve, a cam operable therein, a spring connected at one end to the sleeve and at the other end to said cam for rotating the same, and means for checking said cam upon movement thereof in response to the operation of said spring, said cam being provided with a flat which permits rotation thereof without corresponding movement of said piston.

W. L. SHEPPARD.
